UNITED STATES PATENT OFFICE.

WALTER P. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,281,634.

Specification of Letters Patent. Patented Oct. 15, 1918.

Application filed September 28, 1917. Serial No. 193,847.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

My invention relates to outside metal car roofs of the general type shown in Hoffman Patent No. 999,166, patented July 25, 1911. In roofs of this type, the eaves ends of the roof sheets are re-bent on the under side to movably interlock with a re-bent flashing member of sheet metal secured to the sub-structure. Heretofore, it has been customary in actual practice to use clips secured to the substructure at the eaves and extending inwardly to overlap the ends of the roof sheets or of the seams thereof for the purpose of holding the sheets movably in position, said clips being used in conjunction with the sheet metal flashing. The principal object of the present invention is to dispense with the clips and thereby save the cost thereof, avoid the rust and wear of the sheets incidental to the use of the clips, and avoid the effects of accidental loss of the clips in service.

In the accompanying drawing, which forms part of this specification, and wherein like numerals refer to like parts wherever they occur,

Figure 1 is a view of a portion of an outside metal car roof embodying my invention, with the roof sheets indicated in broken lines;

Fig. 2 is a similar view showing a modified form of flashing holder;

Fig. 3 is a like view illustrating still another form of flashing holder; and

Fig. 4 is a detail view of the flashing holder illustrated in Fig. 3.

Fig. 5 is a fragmentary plan view of the eaves portion of the car provided with the flashing holder shown in Fig. 1;

Fig. 6 is a vertical cross-section taken adjacent to the roof seam on the line 6-6 in Fig. 5; and

Fig. 7 is a side elevation of the eaves portion of the car in the region of the roof seam.

The construction illustrated in the drawing comprises a common type of side plate 1, side sheathing 2, fascia 3, and wooden roof sheathing 4. The upper edge portion

of the roof sheathing is rabbeted or offset to a lower level than the main surface of the sheathing; and in the rabbet 5 thus formed lies the sheet metal flashing strip 6. The body portion of this flashing strip rests 60 flatwise on the rabbeted portion of the sheathing, and has its inner margin 7 bent or folded back over the body portion, but spaced slightly therefrom; and the outer margin 8 of the flashing strip is bent down 65 over the eaves and secured by nails 9 to the side of the car. The metal roof sheets 11 have their eaves end portions re-bent on the under side as at 12 to interlock movably with re-bent inner margins or flanges 7 of the 70 flashing strips; and at or near the ridge of the car, the sheets are secured in any suitable manner against sliding crosswise off of the car,—in such a way, for instance, as shown in Posson Patent No. 1,015,340. In the construction illustrated, the roof sheets are loosely connected along their side margins by interlocking seams 13, which are made by overlapping the rebent side marginal portions of the roof sheets.

In the construction illustrated in Figs. 1, 5, 6 and 7, a strip 10 of metal or other suitable material is disposed above the flashing strip and nailed at its inner end to the wooden sheathing, and at its outer end is bent down 85 and nailed to the side of the car. This strip 10 thus serves to prevent the flashing strip from bending up and becoming disengaged from the roof sheet, as might otherwise be liable to occur in the case of a severe wind-storm. As this strip 10 that serves to hold or reinforce the flashing strip extends entirely across the flashing, it is located beneath the joint or seam 13 between adjacent roof sheets 11, the corner portions of the 90 roof sheets being cut away instead of being rebent. In order that this strip may better serve to shed the water, the upper surface thereof or of the exposed portion thereof is concaved or dished, as illustrated.

The flashing holding or reinforcing strip 10 illustrated in Fig. 2 is intended for use away from the seam or joint between the roof sheets; that is, in the middle region of the roof sheet; and in order to avoid the necessity for cutting away a part of the roof sheet, the holding or reinforcing strip terminates flush with or short of the edge of the hook portion of said flashing. In this case, the flashing holding or reinforcing

strip should be a stiff member with its inner end nailed close to the rabbet; and it is desirable to concave or dish the upper surface of this strip to stiffen it and better drain 5 any water that may fall thereon.

In the construction illustrated in Fig. 3, the strip 10^b that holds or reinforces the 10 flashing is beneath the flashing strip throughout the greater portion of its length, but has its inner end rebent to overlie the 15 flashing and thereby reinforce it. In this case, the holding strip is nailed to the sub-structure before the flashing strip is applied, and preferably also before its inner end is rebent. In such case, the flashing strip covers the nails 9 through the securing strips as well as the nails 12^c that hold the wooden 20 sheathing to the substructure.

What I claim is:

- 20 1. In an outside metal car roof comprising roof sheets whose eaves end portions are rebent and movably interlocked with rebent flashing strips, strips for reinforcing the flashing strip, said reinforcing strips being fastened to the substructure and having portions overlapping the rebent portions of the flashing strips.
- 25 2. In an outside metal car roof comprising

30 roof sheets having their eaves end portions rebent and movably interlocked with rebent 35 flashing strips, a strip for reinforcing the flashing strip, said reinforcing strip being fastened to the substructure at its inner end and having a portion overlapping the rebent portion of the flashing strip.

3. An outside metal car roof comprising 40 roof sheets whose eaves end portions are rebent and movably interlocked with rebent 45 flashing strips, a strip for reinforcing the flashing strip, said reinforcing strips crossing said flashing strips under the roof seams and having their ends secured to the sub-structure beyond the flashing strips.

4. An outside metal car roof comprising 50 roof sheets having their eaves end portions rebent and movably interlocked with rebent 55 flashing strips, a strip for reinforcing the flashing strip, said reinforcing strip having its upper surface concaved and being fastened to the substructure, and having a portion overlapping the rebent portion of the flashing strip.

Signed at Chicago, Ill., this 25th day of September, 1917.

WALTER P. MURPHY.
